US00D803071S

(12) **United States Design Patent** (10) **Patent No.:** **US D803,071 S**
(45) **Date of Patent:** **** Nov. 21, 2017**

(54) **BOTTLE HAVING THREE COMPARTMENTS**

(71) Applicant: **Daniel Telu-Zoltner**, Bucharest (RO)

(72) Inventor: **Daniel Telu-Zoltner**, Bucharest (RO)

(**) Term: **15 Years**

(21) Appl. No.: **29/568,209**

(22) Filed: **Jun. 16, 2016**

(51) LOC (10) Cl. **09-01**

(52) U.S. Cl.

USPC **D9/747**

(58) **Field of Classification Search**

USPC ..... D9/741, 516, 529, 559, 564–566, 561, D9/562, 575, 737, 738, 686, 689, 691, D9/693, 570, 574, 747, 569, 573, 620, D9/341, 367, 751, 756, 530, 313, 375, D9/403, 409, 413, 558, 547, 743, 744, D9/539–546, 520–524; D7/509–511, D7/563, 573, 513, 300, 308, 312, 315, D7/601, 602, 619.1, 622; D3/202; 264/532; 222/129, 94, 135; 220/505, 220/504, 288, 709, 23.4, 23.8, 23.88, 633, 220/916, 660, 669; 215/6, 10, 1 R, 1 C, 215/379, 381–384

(57) **CLAIM**

The ornamental design for a bottle having three compartments, as shown and described.

DESCRIPTION

FIG. 1 is a perspective view of the bottle having three compartments;

FIG. 2 is a front perspective view of the bottle having three compartments of FIG. 1;

FIG. 3 is a rear perspective view of the bottle having three compartments of FIG. 1;

FIG. 4 is a left side perspective view of the bottle having three compartments of FIG. 1;

FIG. 5 is a right side perspective view of the bottle having three compartments of FIG. 1;

FIG. 6 is a top plan view of the bottle having three compartments of FIG. 1; and,

FIG. 7 is a bottom plan view of the bottle having three compartments of FIG. 1.

The broken lines shown illustrate portions of the bottle having three compartments and form no part of the claimed design.

1 Claim, 7 Drawing Sheets
